United States Patent Office

Des. 193,165
Patented July 10, 1962

193,165

SIGN

Archie F. Parrish and Lucian Houze, Roanoke, and John
W. Inge, Jr., Bedford County, Va., assignors to Far-
rows, Inc., Roanoke, Va., a corporation of Virginia

Filed Sept. 7, 1961, Ser. No. 66,634

Term of patent 14 years

(Cl. D1—12)

Fig. 4

FIGURE 1 is a side elevational view of a sign showing our new design, the opposite side being a mirror image thereof;

FIGURE 2 is an end elevational view thereof taken from the left of FIGURE 1;

FIGURE 3 is an end elevational view thereof taken from the right of FIGURE 1; and

FIGURE 4 is an enlarged fragmentary elevational view of the center portion thereof.

We claim:

The ornamental design for a sign, substantially as shown and described.
